(57) **CLAIM**

The ornamental design for a deer bobble toy, as shown and described.

DESCRIPTION

FIG. 1 is a front perspective view of a deer bobble toy according to a preferred embodiment of the present invention, showing a head portion in motion;

FIG. 2 is a first side perspective view of a deer bobble toy according to a preferred embodiment of the present invention, showing a head portion in motion;

FIG. 3 is a second side perspective view of a deer bobble toy according to a preferred embodiment of the present invention, showing a head portion in motion;

FIG. 4 is a rear perspective view of a deer bobble toy according to a preferred embodiment of the present invention, showing a head portion in motion; and,

FIG. 5 is a bottom perspective view of a deer bobble toy according to a preferred embodiment of the present invention, showing a head portion in motion.

The broken line showing of the arrow is for illustrative purposes to illustrate the motion of the head, and forms no part of the claimed design.
